[57] CLAIM

The ornamental design for a putting training aid, as
shown and described.

DESCRIPTION

FIG. 1 is a perspective view of a putting training aid
showing my new design;

FIG. 2 is an enlarged top plan view thereof;

FIG. 3 is an enlarged right side elevational view
thereof, the left side elevational view being a mirror
image;

FIG. 4 is an enlarged bottom plan view thereof;

FIG. 5 is an enlarged front elevational view thereof;

FIG. 6 is an enlarged rear elevational view thereof; and,

FIG. 7 is a reduced bottom plan view of a second em-
bodiment of the design of FIG. 1; all other surfaces
being identical.
